UNITED STATES PATENT OFFICE.

GUSTAVUS H. BOEHMER, OF ST. LOUIS, MISSOURI.

SHOE LAST.

Application filed February 26, 1925. Serial No. 11,786.

To all whom it may concern:

Be it known that I, GUSTAVUS H. BOEHMER, a citizen of the United States, and a resident of St. Louis, and State of Missouri, have invented a new and Improved Shoe Last, of which the following is a full, clear, and exact description.

This invention relates to shoe lasts, an object of the invention being to provide a last of improved shape which gives to the shoe sole formed thereon a contour which conforms to the contour of the normal foot so as to prevent the foot from spreading out of shape or compressing the arches either longitudinally, vertically or transversely so as to impair circulation and prevent the foot from functioning properly.

In shaping the last I have in mind the formation of a shoe sole which will follow the normal lines of the bottom of the foot and give support not only to the arches, both longitudinal and metatarsal, but make provision for direct support of the bones of the foot. As for example, I provide a last which so shapes the sole that the latter will hold and support the following bones in their proper or normal position, namely, the five metatarsal bones, each and every one of the three cuneiform bones, also the scaphoid bone, the cuboid bone and the os-calcis bone, in such a manner that they cannot spread out of shape nor can they be crowded together. At the same time the bone structure, muscles, and the arteries and veins of the foot will be able to function properly while sustaining the entire weight of the body.

In other words, it is the purpose of my improved last to so shape a shoe sole that it will place upon each and every bone, ligament and muscle its proper duty, at the same time will maintain the arches of the foot in normal position and prevent either spreading, or contraction, or collapsing of any of the arches of the foot.

The broad purpose, therefore, of my invention is to provide a last upon which a sole may be shaped which will hold the foot in the same shape when the weight is thereon as when the foot is free from weight, and which will result in obviating or preventing foot troubles, and also as a means for remedying foot ailments.

With these and other objects in view, the invention consists in certain novel features of construction and combinations and ar-

rangements of parts, which will be more fully hereinafter described and pointed out in the claims.

In the accompanying drawings—

Figure 1 is a view in side elevation illustrating my improved shoe last;

Figure 2 is a bottom plan view of the last;

Figure 3 is a view in transverse section on the line 3—3 of Figure 1;

Figure 4 is a view in transverse section on the line 4—4 of Figure 1;

Figure 5 is a view in transverse section on the line 5—5 of Figure 1.

I shall first describe the shape of the last and later the function or reason for such shape. 1 represents the last, which for convenience of description may be divided into three parts, namely, the heel portion 2, the toe portion 3, and the arch portion 4, although these parts constitute a single integral member and may be made of wood or any other suitable material or combinations of material.

My invention has to do more particularly with the shape of the bottom of the last, and it will be noted that I provide a longitudinal transversely curved arch or recess 5 extending from the heel portion 2 to the toe portion 3, this recess or arch increasing in depth from the heel to a point slightly removed from the heel, then extending longitudinally in substantially the same depth, and merging into a transverse curved line 6 at the rear of the toe portion or ball of the foot.

This curve 6 at its ends merges into forwardly extending curved portions 7 at opposite sides of the bottom of the last, and the sides of the arch portion of the last at the bottom thereof are convexly rounded or curved as shown at 8.

It will thus be noticed that the shape of the bottom of the last is such that it gives a transverse arch from a point adjacent the heel to a point at the center of the ball. This curve or recess while extending longitudinally gives the transverse arch shape desired; which at its outer edges is convexly curved or rounded so as to provide a last which will shape a sole that will exactly conform to the shape of a normal foot.

The cross sectional views 3, 4 and 5 show how the lines of curvature change or vary from the heel to the toe portion of the last.

Having now described mechanically the shape of the last, I will describe the func-

tion of such shape, bearing in mind that I have reference to the sole which is made upon such a last with a view to setting forth the contour as compared with and as a support for the various bones of the foot.

The contour of the bottom or under side of the last is so shaped that it conforms to the shape of the normal foot, and a sole made upon such last will be of such shape that the skeleton or bone structure of the foot will be held in the same natural position when sustaining the weight of the body as when it is not sustaining any weight at all. This is accomplished in the following manner:

The dividing line on the bottom of the last, at the break where the ball ends and the shank begins. This line on all lasts that I have ever seen curved toward the heel. On this last the line is reversed and curves toward the toes, directly back of the forward ends of the five metatarsal bones, allowing sufficient space for all of them to rest comfortably. From this line the last is hollowed out to support the natural curves of the following bones, beginning with the first metatarsal bone which is joined to the big toe, gradually curving up to support the second metatarsal bone, then further up to support the third metatarsal bone, then gradually curving down to the fourth metatarsal bone, and, still further down, to support the fifth metatarsal bone, then back toward the heel of the last, following every curve as near as possible, going up under the five metatarsal bones to where they meet the three cuneiform bones and the cuboid

bone, then down and in under the cuboid bone and the three cuneiform bones, and up to where the os calcis and astragalus bones rest upon the heel.

Various slight changes and alterations might be made in the general form of the parts described without departing from my invention, and hence I do not limit myself to the precise details set forth but consider myself at liberty to make such slight changes and alterations as fairly fall within the spirit and scope of the appended claims.

I claim:

1. A shoe last having a longitudinal transversely curved arch in its bottom face extending from the heel portion thereof to the ball thereof, the outer portions of said arch being convexly curved and the central portion concavely curved, the center line of said concaved portion also tapering longitudinally from heel to tread. 55

2. A shoe last having a longitudinal transversely concaved curved arch in its bottom face extending from the heel portion thereof the center line of which curves or tapers longitudinally to the ball thereof, the outer portions of said arch being convexly curved, said longitudinal arch merging at its forward end into a transversely curved line at the ball of the foot, this curvature being at its center nearest the forward end of the ball and at its ends merging into oppositely curved lines which merge into the lateral curvature of the first-mentioned arch. 60 65 70
